AIR DUCT REGISTER

Edwin A. Jones, Milwaukee, Wis., assignor to
 L. J. Mueller Furnace Company, Milwaukee,
 Wis., a corporation of Wisconsin

Application October 7, 1933, Serial No. 692,576

6 Claims. (Cl. 98—114)

This invention relates to improvements in air duct registers.

In warm air heating, ventilating and air conditioning systems, a room of the building has the open end portion of a pipe or stack entering thereto. It is the practice to apply to the end of the stack or pipe a register which is mounted against the wall into which the pipe or stack extends.

Heretofore, in most register constructions and installations it has been very difficult, if not impossible, to effect a gas tight connection between the register and the end of the stack which will prevent leakages around the register with resultant streaking and discoloration of the wall.

15 The Jones and Wagner co-pending application Serial No. 667,314, filed April 22, 1933, discloses a construction which overcomes the above objection by providing an arrangement which will effect a gas tight seal between the register and the end of the stack. While this construction has been very efficient and practical in use, it has been found that installations of said construction give some difficulty to unskilled workmen.

It is, therefore, the primary object of the present invention to provide an air duct register construction wherein the end of the pipe or duct is connected with the register in such a manner that a gas tight seal will be effected which will prevent leakage around the register, the construction, moreover, being simple and susceptible of easy installation with a minimum amount of time and effort.

A further object of the invention is to provide an air duct register wherein the parts thereof, 35 including the register face or grille, are readily separable and removable, and which, when in place, is securely held against undesired disengagement.

A further object of the invention is to provide 40 an air duct register wherein the register face or grille will lie flatly against the surface of the wall and wherein there will be no exposure of the periphery of the wall opening into which the stack extends, due to shrinkage as between the register face and wall.

A further object of the invention is to provide 45 a register construction, which, irrespective of its length or size, is readily attachable to studding having standard spacing.

50 A further object of the invention is to provide an air duct register which is of very simple construction, is inexpensive and easy to manufacture and install, is neat and attractive in appearance, and is well adapted for the purposes set forth.

With the above and other objects in view the invention consists of the improved air duct register, and its parts and combinations as set forth in the claims, and all equivalents thereof.

In the accompanying drawing in which the same reference characters indicate the same parts in all of the views:

Fig. 1 is a front view of the improved air duct register shown mounted on studding, a portion of the grille being broken away to show constructional details;

Fig. 2 is a longitudinal sectional view taken on line 2—2 of Fig. 1 and showing the application of laths and plaster over the attaching flanges;

Fig. 3 is a fragmentary detail sectional view taken on line 3—3 of Fig. 1 and on a larger scale;

Fig. 4 is a fragmentary detail sectional view taken on line 4—4 of Fig. 1 and on a larger scale; and

Fig. 5 is an enlarged fragmentary detail sectional view illustrating a modification of the invention.

Referring now more particularly to the drawing, it will appear that the register is adapted for installation in a wall having an opening 8 therein between studding members 9 which have the usual spacing arrangement of sixteen inches between centers. The outer end portion of a pipe or stack 10 extends into said opening 8 and said pipe end portion is adapted to have the improved register construction applied thereto. To adapt the end portion of the pipe or stack for connection with the improved register it is necessary that the four corner portions of the pipe be slit inwardly a substantial distance, the said slits being indicated by the numerals 11 in the drawing. The portions of the pipe end separated from one another by said slits are bent outwardly at slight angles to the planes of the pipe walls there adjoining, forming yielding sheet portions 12.

To provide a means of mounting the register and to frame the opening 8, a rectangular metallic frame indicated generally by the numeral 13 is provided. Said frame is formed with end flanges 14 and side flanges 15, all flat and in the same plane. Adjoining the inner edges of said flanges 14 and 15 the metal is bent outwardly at right angles to said flanges as at 17, and then outer face ribs 16 are formed by the metal being bent at right angles to the portions 17. Bent inwardly from the inner edges of the ribs 16 are inwardly angled stack engaging flanges 18.

Ordinarily the studding members 9 are sixteen inches between centers and irrespective of the size of the central opening in the frame 13, the

100

105

110

flanges 14 are sufficiently long to engage adjacent studding members 9, and the frame is secured thereto by nails or screws 19 driven through said flanges and into the studding. If an extremely long register is desired an elongated frame may be provided which will span an intermediate studding member and be attached to studding members on thirty-two inch centers.

- 10 The register face or grille 20 is a rectangular metallic sheet, and, save for a substantial margin, is formed with alternate openings and bars, or is of lattice-work or other ornamental, open-work design, whereby air may freely flow therethrough. Welded or otherwise secured to the inner face of 15 the marginal portion of the grille, substantially inwardly of the edge portion thereof, is a sealing and grille locating frame 21. Legs 22 of said sealing frame are biased inwardly slightly from perpendicular to the inner face of the grille and 20 said legs are formed of yieldable metal. The free end portions of said legs are formed with inwardly turned guiding rolled portions 23.

When the improved register is to be assembled and installed the inner end portion of the pipe 25 or stack 10 is first provided with the corner slits 11, as previously described. The metallic frame 13 is next positioned in the wall opening 8 and is secured to faces of the spaced studding members 9. The yielding sheet portions 12 of the 30 stack, defined by the slits 11 are positioned adjacent and bent toward face portions of the flanges 18 of the frame 13. The next step is the positioning and attaching of the register face or grille 20. The grille is correctly located by 35 the legs 22 which enter the frame opening and said legs, being inwardly inclined, slide along the stack portions 12 and when the grille is in position said legs yieldingly impinge against said stack portions and securely clamp said stack portions against the frame flanges 18. In this way 40 a gas-tight seal is effected between the inner end portion of the stack and the register frame. The register face or grille is removably held in position by means of screws 24 passed through corner 45 openings in the grille and into portions of the ribs 16 of the frame. With the grille resting against the frame ribs 16, said face is removed laterally outwardly from the faces of the studding 50 9. Lathing 25, and plaster 26 is built up outwardly of the flanges 14 to the plane of the ribs 16 to complete the room wall around the opening 8.

In the modified form of air duct register disclosed in Fig. 5 the stack 10 is formed in the 55 manner previously described with slits 11 defining yielding, outwardly bent sheet portions 12. The frame 13' is formed with a rectangular outwardly projecting collar surrounding the opening through the frame. Said collar is formed by portions 17' flanged outwardly from the inner margins of the end flanges 14' and the side flanges, said portions 17' being at acute angles to said end and side flanges. Projecting outwardly from the ends of the portions 17' in planes parallel 65 to the planes of the end and side flanges, are grille engaging flanges 16'. The inner face of the register face or grille 20, inwardly of its outer margin, carries an inwardly projecting frame having inwardly inclined legs 22'. The register grille 70 is positioned so as to rest on the flanges 16' and is secured thereto by screws 24, while the legs 22' impinge against the stack portions 12 and clamp the same against the inner frame portions 17' to provide a seal between the stack end portion 75 and the register frame.

The improved air duct register construction is one which has great utility in heating, ventilating and air conditioning system installations. By reason of the construction disclosed a gas tight joint is effected between the stack end and the register frame. The register face is easily pushed into position and properly located and this action also serves to secure the connection between the stack and frame. The component parts of the device are easily manufactured and installation and assembly of the construction can be easily undertaken by an unskilled workman. After assembly the grille can be removed whenever desired for repairs or cleaning operations.

80 From the foregoing description it will be seen that the improved air duct register is both simple and novel, and is well adapted for the purposes described.

85 What is claimed as the invention is:

90 1. An air duct register, comprising an inner frame having a flange extending at an angle to the plane of the frame, a grille mounting flange joining said first flange and laterally removed from the plane of the frame, and a grille mounted against said second flange and having an inwardly extending flange for clamping a pipe end portion between it and the first flange of said frame.

95 2. An air duct register, comprising an inner frame having an opening therethrough, a collar 105 surrounding said opening and inclined toward the outer marginal portions of said frame, a grille mounting flange carried by said collar in a plane outwardly of and parallel with the plane of the frame, a grille mounted against said flange, and 110 clamping flanges projecting inwardly from the inner face of the grille and locating within said collar and closely thereadjacent for clamping a pipe end portion against said collar.

115 3. An air duct register, and a stack cooperable therewith, the inner end of said stack having yielding outwardly flared portions, said register comprising an inner frame having an opening therethrough into which said pipe end portion extends, a collar surrounding said opening and 120 inclined toward the outer marginal portions of said frame and engaging said flared end portion of the stack, a grille mounting flange carried by said collar in a plane outwardly of and parallel with the plane of the frame, a grille mounted 125 against said flange, and clamping flanges projecting inwardly from the inner face of the grille and impinging against the flared end portions of said stack to clamp the same against said collar.

130 4. An air duct register, and a stack cooperable therewith, said stack having its inner end portion formed with separated, outwardly bent yielding sheet portions, said register comprising an inner frame having an opening therethrough into which said sheets extend, a collar surrounding 135 said opening and inclined toward the outer marginal portions of said frame and engaged by said stack sheet portions, a grille mounting flange carried by said collar in a plane outwardly of and parallel with the plane of the frame, a grille removably secured against said flange, and a clamping frame secured to the inner face of said grille inwardly of its marginal portions and having legs extending adjacent said collar and impinging against the sheet portions of the stack to clamp 145 the same against said collar.

140 5. In combination, a register including an inner frame having an opening therethrough and a collar integral with said frame and surrounding the opening and inclined toward the outer mar- 150

ginal portions of said frame, said frame also having a flange connected with said collar and disposed in a plane outwardly of and parallel with the plane of the main frame portion, a pipe extending into said collar, the portion of the pipe extending into said collar being formed with outwardly bent, separated, yielding sheet portions detachably engaging said collar, a grille removably secured to said frame flange, and a clamping and grille locating frame secured to the inner face of said grille inwardly of its marginal portions and having legs extending adjacent said collar

and impinging against the sheet portions of the stack to clamp the same against said collar.

6. An air duct register, comprising an inner frame having a flange at an angle to the plane of the frame, a grille mounting flange joining said first flange and laterally removed from the plane of the frame, a grille secured to said grille mounting flange, and a sealing frame interposed between the grille and the inner frame and having an inwardly extending flange for clamping a pipe end portion between it and the first flange of the inner frame.
